WATER DRIVE FOR WASHING MACHINES

Earl S. Burdick, Milwaukie, and Charles R. Thomson, Portland, Oreg., assignors to Klosterman Inc., Portland, Oreg.

Application December 20, 1930
Serial No. 503,779

3 Claims. (Cl. 121—121)

This invention relates generally to washing machines, and particularly to one of small dimensions in which water is employed to operate the prime mover thereof.

- The main object of this invention is to provide a novel form of washing machine and drive therefor especially adapted for use in localities where electric power is not available or too expensive.
- 10 The second object is to provide a novel form of prime mover which will be water operated, quiet in operation, simple to manufacture and devoid of delicate or intricate parts.

The third object is to provide a water propelled washing machine in which the propelling water can be employed for rinsing purposes if desired.

These, and other objects, will become more apparent from the specification following as illustrated in the accompanying drawings, in which:

- Fig. 1 is a side elevation of the machine.
- Fig. 2 is an end elevation.
- Fig. 3 is a vertical section taken along the line 3—3 in Fig. 1.
- 25 Fig. 4 is a longitudinal section along the line 4—4 in Fig. 2.

Fig. 5 is a vertical section through the prime mover showing the valve in a running and rinsing position taken along the line 5—5 in Fig. 14.

30 Fig. 6 is a view similar to Fig. 5 showing the valve reversed but still in a running and rinsing position taken along the line 5—5 in Fig. 14.

Fig. 7 is a front elevation of the prime mover taken along the line 7—7 in Fig. 4.

35 Fig. 8 is a view similar to Figs. 5 and 6 but showing the parts set for a running non-rinsing position taken along the line 5—5 in Fig. 14.

Fig. 9 is a view similar to Fig. 8 but showing the parts in the extreme opposite non-rinsing position for running the machine taken along the line 5—5 in Fig. 14.

40 Fig. 10 is similar to Fig. 9 but showing the parts in a cylinder filling non-running position taken along the line 5—5 in Fig. 14.

Fig. 11 is a section taken along the line 11—11 in Fig. 4.

Fig. 12 is a view similar to Fig. 11 showing the valve just passing over its center.

50 Fig. 13 is a view similar to Fig. 12 showing the valve in one extreme position.

Fig. 14 is a section taken along the line 14—14 in Fig. 12.

Fig. 15 is a section taken along the line 15—15 in Fig. 12.

Fig. 16 is a section taken along the line 16—16 in Fig. 12.

Similar numbers of reference refer to similar parts throughout the several views.

Referring in detail to the drawings, the device 60 consists principally of three elements, namely a rockable cylinder 20 and supporting frame 21 at one end of the cylinder, and a second supporting frame 22 at the opposite end of the cylinder which constitutes a housing for the prime 65 mover. The cylinder 20 is provided with a removable closure 23 which can be snapped into position to facilitate its removal and application to the cylinder.

The cylinder 20 has its end 24 provided with a 70 trunnion 25 which journals in the frame 21. The cylinder 20 has its end 26 provided with an elongated trunnion 27 which has an opening 27—A formed therethrough along its entire length. The trunnion 27 journals in the side wall 28 of 75 the frame 22. On the trunnion 27 is keyed a curved arm 29 with projecting stops 30 formed at opposite ends thereof, which are outside of the curved face 31 of the arm 29.

Rising from the floor 31—A is the lower back 80 wall 32 which does not join the lower end of the wall 28. Outside of the wall 32 is formed a flange 33 which, with the wall 32, forms a catch basin having an outlet 34 at the bottom thereof. The side frames 21 and 22 are held in spaced relation 85 by means of the tie rods 35.

The cylinder 20 is provided with a waste cock 86 which discharges into the catch basin formed by the wall 32 and the flange 33 when the handle 37 of the cock 36 is placed in the open position. 90

The front of the frame 22 is provided with an opening 38 through which can be inserted the block of the prime mover. This consists of a pair of parallel cylinders 39, preferably upright and having their lower ends closed by means of 95 the heads 40 and which are held in spaced relationship by a cross tie 41 in which is rotatably mounted a trip valve 42 having an enlarged end portion 43, a reduced intermediate portion 44 and a still further reduced end portion 45 which projects through the closed end 46 of the tie 41 and has mounted on the outer end thereof a full throw disk 47 on which is pivoted the head 48 of the spring pin 49 whose upper end passes through the rockable guide 50. A spring 51 is mounted on the pin 49 between the guide 50 and the head 48. The guide 50 is mounted on the up-standing portion 52 of the cross tie 41. The head 48 lies between the stops 30.

Journalized in the cross tie 41 is the trip valve 110

42 which is provided with an annular passageway 53 which does not, however, extend completely around the valve but terminates radially to form the ports 54 and 55 which communicate laterally with the ports 56 and 57, which communicate with the interiors of the cylinders 39. In the bottom of the cross tie 41 is a waste port 58. In the exterior of the trip valve 42 is formed a passageway 59 adapted to connect the waste port 58 with either of the ports 56 or 57, depending upon its position.

10 Into the member 42 there projects the manually rotatable control valve 60 which has an opening along almost the entire length thereof 15 and which has one side of its innermost closed end 61 cut away as shown in Figs. 5 and 14. The control valve 60 is provided with a cutaway portion 62 which is adapted to register with the opening 63 in the passageway 53. The control valve 60 is provided with an opening 64 which extends across its closed end a short distance therefrom and can register with the opening 65 in the trip valve 42, which opening can register with the opening 66 in the top of the cross tie 41. A pipe 25 67 connects the opening 66 with the outer end of the trunnion 27. The valve 60 is provided with an encircling flange 68 by means of which it is held within the trip valve 42 by the cap 69 through which the valve 60 projects.

30 Over the opening 38 is placed a cover plate 70 which forms a bearing for the valve 60 on the outer end of which is placed a dial 71 by means of which the valve 60 may be placed in either the rinse position 72, the run position 73 or the fill 35 position 74.

On the outer end of the trunnion 27 is mounted a walking beam 75 which is joined at its ends by means of the connecting links 76 to the pistons 77 in the cylinders 39.

40 It is desirable to provide the interior of the cylinder 20 with a pair of longitudinal ribs 78 and 79 for the purpose of expediting the tumbling action of the articles being washed.

45 The operation of the device is as follows: Assuming that clothes have been placed in the cylinder 20 and that the dial 71 has been turned to the fill position 74 and that the valve 60 has been coupled up to a water supply line, preferably by means of a hose, the parts will now be 50 in the position shown in Fig. 10 in which water can flow directly from the valve 60 through the openings 64, 65 and 66, and then through the pipe 67 into the cylinder 20.

55 When a sufficient amount of water is admitted to the cylinder 20 the dial 71 is turned to the run position (as shown in Fig. 9) in which it will be noted that the opening 64 does not register with the opening 65, but the opening 62 does register with the opening 63, causing the pistons 77 to move, and, through the member 29, to reverse the trip valve 42.

60 Obviously, unless some means is provided for insuring the completion of the rocking movement of the trip valve 42 in either direction the device 65 could not function properly, and it is for this reason that there is provided the full stroke mechanism, including the members 29 and 47 to 50 inclusive, which causes the cylinder 20 to be rocked to and fro as long as the parts are in the foregoing position.

70 If the dial 71 is now turned to the rinse position (as shown in Figs. 5 and 6) the cylinder will be rocked and water admitted to the cylinder for rinsing purposes while it is in motion.

75 It must be understood that the control valve 60

does not rock with the trip valve but is held in one of the positions 72, 73 or 74 by means of a spring-urged ball 60—A which is mounted in the plate 70 and consists in corresponding depressions in the valve 60.

80 It can thus be seen that by a very simple arrangement of parts an economical quiet running machine has been produced which, under the control of one valve, allows the machine to be filled or operated for washing purposes or used for rinsing purposes.

85 We are aware that many forms of washing machines have been constructed in the past, therefore we do not claim such devices broadly, but we do intend to cover all such forms and modifications thereof as fall fairly within the appended claims.

90 We claim:

95 1. A water motor comprising a pair of spaced parallel cylinders, an oscillating valve mounted between said cylinders having intake and exhaust channels formed therein, said cylinders having ports formed therein adapted to register with said channels, a tubular control valve within said oscillating valve through which water may enter 100 the intake channels, a walking beam mounted between said cylinders, pistons in said cylinders connected to said walking beam, and a valve actuating mechanism between said walking beam and said valve for oscillating said valve.

105 2. A fluid operated motor having in combination a pair of parallel cylinders, a cross tie between said cylinders, an oscillatable trip valve mounted in said cross tie having communicating passageways between the interior thereof and 110 said cylinders whereby water may be caused to enter or escape from said cylinders, a tubular control valve having an inlet opening at one end and an outlet port near its opposite end, said control valve being adjustably mounted within 115 said trip valve and having another port therein capable of being brought into communication with the passageways in said trip valve, a rock shaft mounted between said cylinders above said trip valve and parallel with the axis of the trip 120 valve, a walking beam secured on said rock shaft, a piston in each of said cylinders connected to said walking beam, an arm secured on said rock shaft having a pair of radially projecting stops, a throw disk mounted on said trip valve, a headed 125 pin having its head pivotally attached to said throw disk and having its opposite end mounted in an oscillatable guide, said head occupying a position between said arm stops, a spring on said headed pin between its head and said oscillatable 130 guide, and a dial for manually setting said control valve with relation to said trip valve.

135 3. A fluid operated motor having in combination a horizontal rock shaft, a walking beam secured to said rock shaft, a pair of vertical parallel cylinders disposed on opposite sides of said rock shaft each of said cylinders having a piston therein provided with a connecting link to its respective end of the walking beam, an oscillatable trip valve for connecting passageways communicating with said cylinders, a normally stationary control valve adjustably mounted within said trip valve, said control valve constituting a means for admitting water to said trip valve, and means actuated from said rock 140 shaft for moving said trip valve to either of its extreme positions of travel at the end of each movement thereof.

EARL S. BURDICK.
